UNITED STATES PATENT OFFICE.

MAX GARBELL, OF CHICAGO, ILLINOIS, ASSIGNOR TO VICTOR ADDING MACHINE COMPANY, OF CHICAGO, ILLINOIS, A CORPORATION OF ILLINOIS.

TYPEWRITER-PAPER FINGER.

Application filed August 1, 1927. Serial No. 209,671.

My invention relates to typewriters and it has particular relation to paper supporting means used in connection with the paper table of a typewriting machine, such means being commonly referred to as paper fingers.

More especially my invention contemplates the provisions of such paper fingers as can be very simply and expeditiously brought into operating position and withdrawn from such position when the same are not needed. It frequently happens, in the manipulation of a typewriter, that some means is desired to support a paper for a considerable distance above the usual paper table.

That such a provision is especially required in a portable typewriter is apparent from the minimum volume requirements and the fact that the paper table must necessarily be compact and small. My invention contemplates providing the usual paper table with paper fingers which may be elevated to support the material being written upon and which, when not required for such support, may be collapsed to minimum volume or space occupying position.

Another of the concomitant objects of my invention is to provide such adjustable paper fingers as may be manufactured very cheaply and applied to the portable typewriter without material increase in the cost of the machine as a whole.

Moreover, I provide a novel motion in connection with my paper fingers or supports so that the same are raised from an inoperative to an operative position with a minimum movement of the actuating means.

My invention will be better understood by reference to the accompanying drawing, in which:

Figure 1 is a perspective view of as much of a typewriter as is necessary to clearly and operatively disclose my invention, the paper supporting fingers being shown in elevated or paper-supporting position;

Fig. 2 is a rear elevational view of the paper table proper of the typewriting machine showing the fingers in collapsed position in full lines and in elevated position in broken lines;

Fig. 3 is a fragmentary sectional view taken on the line 3—3 of Fig. 2; and

Fig. 4 is a fragmentary sectional view taken on the line 4—4 of Fig. 2.

In Fig. 1 I have illustrated in perspective a platen 10 mounted in end frames 11, it being understood that these end frames are adapted for positioning on the carriage portion of a typewriter in accordance with any desired scheme.

Mounted in the end frames and in association with the rotatable platen is a paper table 12. In order to support a paper or other material which is being written upon in such position that an appreciable portion of the written matter may be constantly referred to, I have provided paper supporting means in the form of fingers 13 and 14.

It is desirable and in fact essential when such fingers are used on a portable typewriter, where it is necessary that the parts thereof occupy a minimum amount of space, that these fingers be adjustable or collapsible so that they do not protrude beyond the paper table when in inoperative position.

Referring now to Figs. 2 and 3, I have shown in Fig. 2 the fingers 13 and 14 in elevated position as also in Fig. 1. The finger 13 is pivotally mounted at 15 on a bracket 16 which is secured to the rear of the paper table as shown. The finger 14 is mounted for pivotal movement at 17 on a similar bracket 18. An actuating means comprises members 19 and 20 adapted to be moved by the actuation of a button 21 which is secured to the rear edge of the paper table 12. The member 19 is fastened to the finger 14 at the off-center point 23, and the member 20 is likewise secured at the point 23 on arm 14 and extends around and is secured to the extended portion 24 of the arm 13 at the point 25 thereof. By referring to Fig. 2 it will be noted that when the button 21 is moved longitudinally along the rear edge or overturned portion of the paper table, the fingers 13 and 14 are collapsed into the position shown in said Fig. 2.

Although the parts employed in my novel arrangement are relatively few, it requires a very short motion of the actuating means

21 to raise the finger into operative position. Moreover, the parts are all raised under the overhanging adjustment of the paper table so that they occupy the space normally used 5 for no other purpose. It will be apparent, therefore, to those skilled in the art that I have provided a means whereby a portable typewriter may be equipped with the desirable, and in many cases necessary, paper supporting fingers, and that moreover, I have so arranged the aforesaid fingers that it may be changed from inoperative to operative position very easily.

10 While, therefore, I have described but one embodiment of my invention, it is apparent that others may enlarge the same and through the employment of means which are the full equivalent of those illustrated and claimed without departing from the spirit of my invention, and I desire, therefore, that my invention be limited only by the showing in the prior art and the scope of the appended claims.

I claim:

- 25 1. In a typewriting machine, a paper table and an adjustable auxiliary paper supporting means associated with said table, the latter comprising fingers pivotally mounted for movement from inoperative to operative position, and actuating means comprising an arm having a finger piece slidable along the upper edge of the paper table and connected to said supporting means at off-center points to raise the latter.
- 30 2. In a typewriting machine, a paper table, two paper fingers separately pivoted on the back of said table, a substantially horizontally extending connecting link pivotally connected at its respective ends to one of said fingers 40 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 35 4. In a typewriting machine, a paper table, two paper fingers separately pivoted on the back of said table, a substantially horizontally extending connecting link pivotally connected at its respective ends to one of said fingers 45 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 50 5. In a typewriting machine, a paper table, two paper fingers separately pivoted on the back of said table, a substantially horizontally extending connecting link pivotally connected at its respective ends to one of said fingers 55 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 60 6. In a typewriting machine, a paper table, two paper fingers separately pivoted on the back of said table, a substantially horizontally extending connecting link pivotally connected at its respective ends to one of said fingers 65 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 65 7. In a typewriting machine, a paper table, two paper fingers separately pivoted on the back of said table, a substantially horizontally extending connecting link pivotally connected at its respective ends to one of said fingers 70 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 75 8. In a typewriting machine, a paper table, two paper fingers separately pivoted on the back of said table, a substantially horizontally extending connecting link pivotally connected at its respective ends to one of said fingers 80 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 85 9. In a typewriting machine, a paper table, two paper fingers separately pivoted on the back of said table, a substantially horizontally extending connecting link pivotally connected at its respective ends to one of said fingers 90 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 95 10. In a typewriting machine, a paper table, two paper fingers separately pivoted on the back of said table, a substantially horizontally extending connecting link pivotally connected at its respective ends to one of said fingers 100 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 105 11. In a typewriting machine, a paper table, two paper fingers separately pivoted on the back of said table, a substantially horizontally extending connecting link pivotally connected at its respective ends to one of said fingers 110 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 115 12. In a typewriting machine, a paper table, two paper fingers separately pivoted on the back of said table, a substantially horizontally extending connecting link pivotally connected at its respective ends to one of said fingers 120 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.
- 125 13. In a typewriting machine, a paper table, two paper fingers separately pivoted on the back of said table, a substantially horizontally extending connecting link pivotally connected at its respective ends to one of said fingers 130 below the point of pivotal support of said finger and to the other of said fingers above the point of pivotal support thereof, and a substantially horizontally extending operating member having one end pivotally connected to one of said fingers at a point displaced from the point of pivotal support thereof and having its other end formed as a finger piece slidable along the upper edge of said table to actuate said fingers.

4. In a typewriting machine, a paper table, two paper fingers separately pivoted on the back of said table, a substantially J-shaped connecting link having the end of the straight portion thereof pivotally connected to a portion of one of said fingers extended beyond the point of pivotal support thereof and having the curved end thereof extending around the pivotal support of the other finger and pivotally connected to said other finger at a point between the pivotal support and the paper supporting portion thereof, and actuating means for said fingers comprising a slidable member pivotally connected at one of its ends to said other finger and said connecting link at the point of pivotal connection therebetween.

5. In a typewriting machine, a paper table, two paper fingers pivoted on said table and respectively constituting a lever of the first class and a lever of the third class, a connecting link pivotally connected at its respective ends to said fingers to effect corresponding movement thereof, and actuating means for said fingers.

6. In a typewriting machine, a paper table, two paper fingers pivoted on said table and respectively constituting a lever of the first class and a lever of the third class, a connecting link pivotally connected at its respective ends to said fingers to effect corresponding movement thereof, and actuating means for said fingers comprising a member having one of its ends pivotally connected to one of said fingers at the point of pivotal connection between said one of said fingers and said connecting link.

7. In a typewriting machine, a paper table, two paper fingers pivoted on said table and respectively constituting a lever of the first class and a lever of the third class, a connecting link pivotally connected at its respective ends to said fingers to effect corresponding movement thereof, and actuating means for said fingers comprising a member having one of its ends pivotally connected to one of said fingers at the point of pivotal connection between said one of said fingers and said connecting link and having its other end formed into a finger piece slidable along the upper edge of said table.

8. In a typewriting machine, a paper table, two paper fingers pivoted on said table and respectively constituting a lever of the first class and a lever of the third class, a connecting link pivotally connected at its respective ends to said fingers to effect corresponding movement thereof, and actuating means for said fingers comprising a member having one of its ends pivotally connected to the finger constituting the lever of the third class at the point of pivotal connection between said finger and said connecting link.

9. In a typewriting machine, a paper table, two paper fingers pivoted on said table and

respectively constituting a lever of the first class and a lever of the third class, a connecting link pivotally connected at its respective ends to said fingers to effect corresponding movement thereof, and actuating means for said fingers comprising a member having one of its ends pivotally connected to the finger constituting the lever of the third class at the point of pivotal connection between said finger and said connecting link and having its other end formed into a finger piece slideable along the upper edge of said paper table.

In witness whereof, I have hereunto subscribed my name.
